PORTABLE ILLUMINABLE MIRROR

Bernard L. Fleisher, Beverly Hills, Seymour Katz, Los Angeles, Henry P. Stern, Beverly Hills, and Richard V. Weiss, Los Angeles, Calif., assignors to Bercy, Venice, Calif., a corporation of California

Filed May 9, 1966, Ser. No. 2,211

Term of patent 14 years

(Cl. D86—10)

FIG. 1.

FIG. 3.

FIG. 2.

FIG. 4.

FIG. 5.

FIG. 6.

FIGURE 1 is a front perspective view of a portable illuminable mirror showing our new design, the appearance of the border is uniform and as indicated;

FIGURE 2 is a front elevational view thereof, the light bulbs being omitted in order to show the light recesses;

FIGURE 3 is a side elevational view;

FIGURE 4 is a top plan view;

FIGURE 5 is a rear elevational view; and

FIGURE 6 is a rear perspective view.

The essential features of our design reside in the full line disclosure on the drawing.

We claim:

The ornamental design for a portable illuminable mirror, as shown and described.
